UNITED STATES PATENT OFFICE.

GEORGE T. GIFFORD, OF COLEBROOK, ASSIGNOR OF ONE-HALF TO A. A. CHAPMAN, OF WARREN COUNTY, ILLINOIS.

AUTOMATIC CAR-BRAKE.

SPECIFICATION forming part of Letters Patent No. 350,128, dated October 5, 1886.

Application filed May 1, 1886. Serial No. 200,789. (No model.)

To all whom it may concern:

Be it known that I, GEORGE T. GIFFORD, of Colebrook, in the county of Warren and State of Illinois, have invented certain new and useful Improvements in Automatic Railway-Car Brakes, of which the following is a description, reference being had to the accompanying drawings, in which—

Figure 1 is a side view of a portion of a freight-train and locomotive. Fig. 2 is a central longitudinal vertical sectional view of a freight-car, the same being broken in length and having the box removed to show the novel features enlarged. Fig. 3 is a like view of a part of a car, showing some of the parts in different positions. Fig. 4 is a plan view, in detail, showing the mechanism for automatically braking the cars in the event of the breakage of the coupling; and Fig. 5 is an end view, in detail, of said device.

Like letters of reference indicate like parts in the different figures.

The object of my invention is to provide an automatic car-brake for railway-cars which may be cheap in construction and simple in its operation, and in which the inertia of the car may be utilized in setting the same under normal conditions, means being provided for preventing the automatic action of said brake when the same is not needed.

A further object is to cause said brake to act automatically in the event of one or more cars becoming uncoupled from the train by accident or otherwise, all of which is hereinafter more particularly described, and definitely pointed out in the claims.

In the drawings is shown an ordinary freight-car, to the body or bed A of which my improved device is attached.

Supported in suitable bearings in suspended brackets b b' , attached rigidly to the bottom of the car, I place at each end of said car and extending in opposite directions a push-bar, B, the same being free to move longitudinally in its bearings, except that it is held normally in an extended position, as clearly shown in Fig. 2, by means of a spiral spring, b^2 . When said bar is normally extended, as stated, the end should project beyond that of the usual draw-bar, a , so as to normally abut against the end of a corresponding push-bar upon the car

in front or rear thereof, as the case may be. Said push-bar B is provided with an enlarged hollow portion or box, b^3 , into the interior end of which is loosely projected a bar, C, pivotally connected to one member of a knee-joint, D, the other member of which is pivoted within said box b^3 . The opposite end of the bar C is pivotally connected to an eccentric, E, suspended from the frame-work of the car and loosely secured thereto in any approved manner, as by a bolt, e . Said knee-joint D is normally straight, being so retained by its own gravity and the action of the spring b^2 and stop e , which hold it in alignment with the bar C, so that when in said normal condition a pressure upon the bar B in the direction of the eccentric E will serve to actuate said eccentric. A lug or projection, d , is attached to one member of said knee-joint, and is extended downwardly through a slot in the box b^3 , as clearly shown in the drawings, which assists by its gravity in retaining said knee-joint in a straight line, but the special purpose of which will be hereinafter more fully stated.

Attached, preferably, to each truck-bolster F, I provide a brake-lever fulcrum, f , to which is loosely bolted a brake-lever, G, the upper end of which is provided with a friction-roller, g , in engagement with the eccentric E. The lower end of said lever is connected with a brake-rod, g' , connected with the brake-beams in any approved manner, but preferably with a secondary brake-lever, G', the fulcrum g^2 of which is attached to the brake-beam g' , the opposite end of said lever being connected with a secondary brake-rod, g^3 , connecting with the opposite brake-beam, said brake-beams being provided with brake-blocks g^4 , suspended in the usual way from the car-body.

Suspended or loosely supported in suitable brackets, h , one of which is best shown in Fig. 2, I provide stirrups H at the respective ends of each car, which straddle the bars B, the ends being free to move in the arc of a circle. The upper ends of said stirrups are connected with each other by means of a rod, h , loosely attached thereto, while to the lower ends of each is loosely attached a horizontal bar, J, which is sustained loosely and is free to reciprocate in a bearing in the bracket b , said bar being placed in such relation to the

lug or trigger *d* that when reciprocated by reason of its connection with the stirrup the bar *J* is raised, thus slightly tilting the knee-joint *D*, so that upon a backward pressure of 5 the bar *B* said knee-joint will be tilted still farther and fail to actuate the bar *C* and eccentric *E*. It is desirable that the stirrups *H H* shall remain normally in a vertical position, and I therefore prefer to pivot them in the middle, and to make the bars *J J* of substantially the same weight as the connecting-rod *h*, so that their inertia, upon suddenly starting or stopping the car, may be counterbalanced by that of said rod, though it is obvious that the 15 stirrup may be pivoted at a point above its middle, provided the top is weighted in a corresponding proportion. As a further means for retaining said stirrups in a normally vertical position, I pivot to the car-sills at *h'*, Fig. 20 2, a bar, *h'*, which is loosely bolted to the rod *h*, and serves to prevent the latter from sagging. Said bar *h'* has rigidly attached thereto a cross-bar, *h⁴*, to one end of which is attached a weight, *h⁵*, and to the opposite end a spiral 25 spring, *h⁶*. As the rod *h* is moved longitudinally the weight *h⁵* is raised or the spring *h⁶* brought under tension, and when the abnormal pressure upon the rod *h* is released the rod is, by the constant tendency of said spring and 30 weight, brought back to its normal position, as shown in Fig. 2. A horizontal bar, *K*, Fig. 1, sustained in loose bearings, is placed beneath the tender, and is connected with the lower end of a lever in the engine-cab and under the control 35 of the engineer, the outer end of said bar abutting against the end of the bar *J*, so that upon moving said lever all of said knee-joints throughout the entire train may be tilted, as described. A buffer-block, *B'*, Fig. 1, is attached 40 to the tender beneath the draw-bar, so that the bar *B* of the car attached to said tender may abut against the same when the motion of the engine is impeded.

Loosely pivoted beneath the car to a pin or 45 stud, *m*, Figs. 4 and 5, attached, preferably, to a block, *m'*, secured rigidly to one of the draft-timbers, is a horizontal lever, *M*, which is extended laterally from the bar *B*, and the inner end of which is in contact with the shoulder 50 formed by the enlargement of said bar, as clearly shown in Fig. 4, so that the bar *B* may be pushed back by pulling forward upon the opposite end of the lever. A chain, *m²*, is permanently attached to the next car, Fig. 4, 55 and is hooked upon the outer end of the lever *M*, which is made sufficiently hook-shaped to retain the same when in its normal position, but will slip off when the lever is drawn forward thereby. At the same time the opposite 60 end of said lever presses the bar *B* back until the end of the bar *M* is brought into engagement with a bevel, *b⁴*, upon the box *b³*, when the movement of the bar *M* ceases and the bar *B* is locked in its backward position thereby, 65 and so retained until the bar *M* is pushed back, when the spring *b²* forces the bar *B* back to its original position.

Having thus described the several elements of my invention, I will now proceed to describe its operation. Assuming a train equipped 70 with said brakes to be in motion, and the several parts in the respective normal positions shown in Fig. 2, upon impeding the motion of the engine, the buffer-block *B'* upon the tender is caused to push back upon the push-bar *B*, and the knee-joint *D*, being preserved in a straight line by, as stated, the bar *C*, is caused to act upon the eccentric *E*, which in turn acts upon the brake-lever *G* and sets the brake, the operation being repeated throughout the train as fast as the forward cars tend to impede the motion of those behind. Should the engineer desire to decrease the speed of his engine without applying the brakes, he can do so by operating the lever *L*, which pushes 80 back the bar *J* and tilts the knee-joint in connection therewith. This motion is transferred by the rod *h* to the opposite end of the car, and is thus repeated throughout the train. If the brakes are applied to a train, the starting of the engine, or an increase of speed, if it is in motion, serves to release them. In case the coupling breaks in any part of the train, the lever *M* is drawn out by the chain *m²*, which actuates the push-bar in the car to which it is attached, and applies the brakes upon that and all the cars behind, leaving them locked until the lever *M* is released. By operating the lever *L* the train may be backed without affecting the brakes. Thus it is obvious that the 90 operation of the brakes of the entire train are under the control of the engineer, who is enabled to manipulate them at will. As no coupling is required in said system, its practicability is apparent. The convenience of switching is greatly enhanced—in short, the many and important advantages of which it is possessed are at once suggested to those familiar with railway appliances upon the explanation of its operation.

I am familiar with the patent to B. L. Stowe, No. 272,097, and I make no claim to the special feature described therein.

What I do claim, and desire to secure by Letters Patent, is—

1. An automatic car-brake consisting of push-bars at the respective ends of the car, means, as spiral springs, for normally extending the outer ends of the same, respectively, in substantially the same transverse plane with the ends of the draw-bar, eccentrics bearing upon the ends of brake-levers having suitable connections with the brake-beams, jointed connections between said eccentrics and push-bars, and means, as a buffer-block, for producing a backward pressure of said push-bars and for abnormally tilting the joints of said connecting-bars, substantially as and for the purposes set forth.

2. In an automatic car-brake, the combination of one or more push-bars loosely supported lengthwise of and beneath the car, one or more eccentrics bearing upon the end of one or more brake-levers having the usual connections with

the brake-beams, said eccentric or eccentrics being connected, respectively, by a rigid bar and knee-joint with said push-bar, a spring for extending said push-bar or bars toward the 5 end or ends of the car, and a buffer-block for producing a backward pressure upon said push-bar upon impeding the motion of the engine, substantially as described, and for the purposes specified.

10 3. The combination, with a railway-car, of the push-bar B, provided with a spring, b², for holding the same normally in an extended position for engaging a buffer upon a car coupled therewith, an eccentric pivoted to the bed of 15 the car and bearing upon the end of a brake-lever having suitable rod-connections with the brake-beams, a bar connecting said eccentric with the push-bar by a knee-joint, D, and means, as the stirrup H and trigger d, for tilting said knee-joint, substantially as and for 20 the purposes specified.

4. The combination of the bar B, provided with a spring, b², for normally extending the same, eccentric E, bearing upon the end of a 25 brake-lever, and means for connecting the same to the brake-beams, bar C, connected by the knee-joint D to the push-bar, means, as the

trigger d, stirrup H, and bar J, for tilting said lever-joint, and a suitable lever and detached or disconnected mechanism, as a bar, K, for pushing said bar J, substantially as and for 30 the purposes described.

5. The combination, with a car, of the push-bars B B, having springs b² b², eccentrics E E, bearing upon brake-levers G G, connected with 35 the brake-beams of their respective trucks, bars C C, connecting said eccentrics and push-bars, respectively, by means of knee-joints D D, having triggers d, bars J J, stirrups H H, connected by a rod, h, and means, as a spring, 40 for retaining said rod in a normal position.

6. In an automatic car-brake, the combination, with a suitable push-bar and mechanism, substantially as described, for setting the brakes, of a pivoted lever, M, and means, as a 45 chain attached to the adjoining forward car, for detachably connecting with said lever, substantially as described, and for the purposes set forth.
